CLAIM

The ornamental design for a step for attachment to land vehicles, as shown and described.

DESCRIPTION

FIG. 1 is a perspective view for a step for attachment to land vehicles showing my new design;

FIG. 2 is a rear view thereof;

FIG. 3 is a front view thereof;

FIG. 4 is a top view thereof;

FIG. 5 is a right side view thereof;

FIG. 6 is a left side view thereof;

FIG. 7 is a bottom view thereof; and,

FIG. 8 is a cross sectional view through the line 8-8 in FIG. 1 thereof.

The step for attachment to land vehicles is shown with a symbolic break in its length. The appearance of any portion of the article between the break lines forms no part of the claimed design.
